US00D761364S

(12) **United States Design Patent**
Summerville, Jr.

(10) **Patent No.:** US D761,364 S
(45) **Date of Patent:** ** Jul. 12, 2016

(54) **CHESSBOARD**

(71) Applicant: **SUMMERVILLE-NEW ENGLAND LLC**, Goshen, CT (US)

(72) Inventor: **Andrew Goodwin Summerville, Jr.**, Goshen, CT (US)

(73) Assignee: **SUMMERVILLE-NEW ENGLAND LLC**, Goshen, CT (US)

(**) Term: **14 Years**

(21) Appl. No.: **29/500,023**

(22) Filed: **Aug. 20, 2014**

(51) LOC (10) Cl. **21-01**

(52) U.S. Cl.
